UNITED STATES PATENT OFFICE.

THOMAS SPOONER, OF PITTSBURGH, PENNSYLVANIA, ASSIGNOR TO WESTINGHOUSE ELECTRIC & MANUFACTURING COMPANY, A CORPORATION OF PENNSYLVANIA.

RHEOSTAT.

Application filed December 17, 1919. Serial No. 345,628.

To all whom it may concern:

Be it known that I, THOMAS SPOONER, a citizen of the United States, and a resident of Pittsburgh, in the county of Allegheny and State of Pennsylvania, have invented a new and useful Improvement in Rheostats, of which the following is a specification.

My invention relates to rheostats such as are commonly used in connection with electrical circuits to vary the resistances thereof.

The object of my invention is to provide a rheostat that is compact in structure, inexpensive in manufacture and durable in use and that may be easily and conveniently operated.

It is customary to provide a rheostat which comprises a resistance element helically wound upon a solid cylindrical member and a movable contact member for shunting turns of the resistor. Such rheostats, as constructed heretofore, possess a number of defects. Resistors having bodies that are solid or that are hollow and are closed at the ends heat with great rapidity. Rigid shunting members having a single contact element wear the resistance element at particular points.

The first of these undesirable features has been eliminated in my rheostat by providing a tubular resistor which is vertically mounted and is cooled by a current of air rising through it. The wear of the resistance element at particular points is avoided by using a helical spring of ring shape as the movable contact member. The coil formation of the spring which surrounds the resistor, permits it to yieldingly engage the resistance element at a number of points, thereby lessening its wear.

For a better understanding of my invention, reference may be had to the accompanying drawing in which Figure 1 is a view, in side elevation, of a rheostat embodying my invention. Fig. 2 is a view in longitudinal, vertical section of the same, and Fig. 3 is a view, in section of the resistor and contact member taken along the line III—III in Fig. 2.

Referring particularly to Figs. 1 and 2, a wound resistor 1 has a slidably-mounted contact member 2 for shunting turns thereof.

The resistor 1 comprises a tubular member 3, a layer 4 of insulating material, such, for example, as asbestos paper impregnated

with a solution of sodium silicate, mounted thereon, and a resistance element 5 helically wound upon the layer 4 and having its ends attached to clamps 6 which are electrically connected to binding posts 7.

The resistor 1 is supported by feet 8 which may be formed by cutting away strips of the material at one end of the tube and bending the remainder outwardly. The openings in the base of the tube formed by removal of the strips permit air to circulate through the tubular member 3.

The slidably mounted contact member 2, shown in Fig. 3 of the accompanying drawing, comprises a ring 9, of molded insulating composition, having an annular groove 10 in its inner face in which is mounted a helical spring 11. The spring 11 which surrounds the resistor 1, is under tension to insure good contact with the turns of the resistance element 5. The ends of the spring 11 are attached to a metallic block 12 that is electrically connected to a binding post 13.

My rheostat may be operated by connecting binding posts 7 to a suitable source of electrical energy to thereby insert the entire resistor 1 in the circuit.

A wire may electrically connect the binding post 13 of the contact member 2 to one of the binding posts 7, thereby permitting the resistance to be gradually shunted, as the contact member 2 is raised or lowered, as the case may be.

The helical form of the spring 11 provides a number of contact points with the resistance element 5, and its resiliency lessens the wear of the element and permits the contact member to be easily moved. A finer adjustment than one turn may be obtained by slightly tilting the contact member 2.

I have shown a simple and preferred form of my invention but the details may be subjected to slight modifications; therefore, I desire that only such limitations shall be imposed as are indicated in the appended claims.

I claim as my invention:

1. In a rheostat, the combination with a coiled resistance element, of a movable contact member of helical shape surrounding said element for gradually shunting turns of the said element.

2. In a rheostat, the combination with a coiled resistance element, of a movable member of helical shape in contact with said ele-

- ment for gradually shunting turns of the said element.
3. In a rheostat, the combination with a coiled resistance element, of a movable contact member of helical shape surrounding said element for gradually shunting turns of said element, and means for effecting movement of said member.
4. In a rheostat, the combination with a wound resistor, of a movable helical contact member at least partially surrounding said member for gradually shunting turns of said resistor.
5. In a rheostat, the combination with a helically wound resistor of substantially uniform cross-section, of a slidable contact member of helical shape surrounding said resistor for gradually shunting turns thereof.
6. In a rheostat, the combination with a vertical tubular resistor having openings at its top and bottom for the circulation of air, of means for shunting said resistor.
7. In a rheostat, the combination with a vertical hollow resistor having openings at its top and bottom for the circulation of air, of means for shunting said resistor.
8. In a rheostat, the combination with a vertical tubular resistor having openings therein for the circulation of air, of means for shunting said resistor.
9. In a rheostat, the combination with a hollow vertical resistor having openings therein for the circulation of air, of means for shunting said resistor.
10. In a rheostat, the combination with a vertical tubular resistor provided with integrally supporting legs thereby permitting air to circulate throughout the length of said resistor, of means for shunting said resistor.
11. In a rheostat, the combination with a coiled resistance element and a casing surrounded by and supporting the said resistance, of a slidably mounted contact member of helical shape surrounding said coil and in contact with said element for gradually shunting turns of said resistance element.
12. In a rheostat, the combination with a tubular member, and a resistance element wound upon said member, of a slidably mounted holder surrounding said resistance element, said holder having a groove therein, and a helical contact member positioned in said groove and in contact with said resistance element for shunting turns of said element.
13. In a rheostat, the combination with a wound resistor of substantially uniform cross section, of a helical contact member surrounding said resistor and under tension to insure intimate contact with said resistor, and means for effecting longitudinal movement of said contact member, thereby gradually shunting turns of said resistor.
14. In a rheostat, the combination with a vertical tubular member having bent flange portions at its base for supporting it and for permitting a current of air to circulate through said member, and a resistance element wound upon said member, of a slidably-mounted grooved holder surrounding said member, and a helical contact member positioned in said groove for shunting turns of said resistance element.
15. In a rheostat, the combination with a vertical metallic tubular member having bent flange portions at its base for supporting it and for permitting a current of air to circulate through the said member, and a resistance element wound upon said member, of a slidably-mounted grooved holder surrounding said member, and a helical contact member positioned in said groove and under tension to insure intimate contact with said resistance element for shunting turns of said element.
- In testimony whereof, I have hereunto subscribed my name this 8th day of December, 1919.

THOMAS SPOONER.
